ARTHUR M. TROGNER, OF EAST ORANGE, NEW JERSEY, ASSIGNOR TO WIRED RADIO, INC., OF NEW YORK, N. Y., A CORPORATION OF DELAWARE

PIEZO-ELECTRIC CRYSTAL APPARATUS

Application filed December 18, 1928. Serial No. 326,813.

My invention relates broadly to piezo electric crystal apparatus and more particularly to a holder for piezo electric crystals.

One of the objects of my invention is to provide a construction of piezo electric crystal holder in which a piezo electric crystal element may be housed for vibration with substantially no restriction, with the edges of the crystal protected against chipping or destruction.

Another object of my invention is to provide a construction of piezo electric crystal holder in which various sizes of piezo electric crystal elements may be housed for vibration with substantially no restraint for delivering maximum piezo electric effect at the terminals of the holder.

A further object of my invention is to provide a construction of piezo electric crystal holder in which a piezo electric crystal element may be compactly arranged within an insulated frame member where the sides thereof are formed to engage edge supporting means while the top and bottom of the piezo electric crystal holder serve as contact electrodes for the crystal within the holder.

A still further object of my invention is to provide a construction of centering member above a piezo electric crystal element for guiding a piezo electric crystal element during the oscillatory motion thereof and for protecting the piezo electric crystal element against breakage during shipment thereof.

Other and further objects of my invention reside in the construction of my invention as described in the specification hereinafter following and by reference to the accompanying drawings in which: Figure 1 is a perspective view showing the assembled piezo electric crystal apparatus of my invention; Fig. 2 is a plan view of the piezo electric crystal apparatus of my invention with the top cover plate removed; Fig. 3 is a lateral cross-section view taken through the piezo electric crystal apparatus illustrated in Fig. 2; Fig. 4 is a fragmentary perspective view of a portion of the insulated holder illustrating the position of one of the sockets which support the centering device or removable bridge in the piezo electric crystal holder and Fig. 5

is a perspective view of the centering device or removable bridge employed in the piezo electric crystal apparatus of my invention.

Piezo electric crystal holders may be broadly divided into two classes according to the usage to which the crystals are to be placed. The first class is that of transmitter crystals where the crystal is required to furnish considerable power and hence must be fairly large and held in the holder in such a manner as to offer the least possible detriment to its action. The second class might be called frequency indicating in that the crystal is mainly used only to maintain the oscillations constant in a relatively feebly oscillating circuit. The crystal therefore need not be as large as in the previous class and the holders need not be as elaborate in the crystal holding features.

The crystal holder of my present invention is more particularly adapted for the frequency indicating class. The crystal holder comprises an insulated body structure having top and bottom cover plates between which the piezo electric crystal is mounted. The frame of the piezo electric crystal holder is provided with longitudinal projections on opposite sides which serve to support the crystal holder in grooves formed in a supporting member. The crystal retainer comprises a flat member or removable bridge apertured at its center which extends parallel to the upper electrode of the piezo electric crystal element. The flat member has tongues on each side thereof which may be disposed at an angle to the plane of the surface of the flat member and project into sockets in the opposite inner walls of frame. The retainer or removable bridge may be of such size as will properly maintain the position of piezo electric crystals of selected thicknesses. When the piezo electric crystal holder is sealed, the crystal is centered in such manner within the holder that the probability of breakage of the crystal in shipment or use is substantially negligible.

Referring to the drawings in more detail, reference character 1 designates the frame of the piezo electric crystal holder provided with longitudinally extending projections 2

at the opposite sides thereof which fit into a grooved support represented at 30. The frame is closed at its top and bottom by means of plates 3 and 4. Screw members 5 and 6 are secured to diagonally opposite corners of the plate 3, and two corresponding screw members disposed at the other two corners hold plate 4 to frame 1; these screws enter the insulated frame structure, as represented at 5a and 6a, in such manner that the capacity loss between the plates is substantially reduced since the screws of opposite plates are not directed towards each other on the same corner but are on different corners of the insulated frame 1. Sockets 7 and 8 are formed in diametrically opposite interior walls of the frame structure 1 to receive the arms 15 and 16 of the retaining member of removable bridge 12. The arms 15 and 16 are cut to suitable length depending upon thickness of crystal employed and bent at an angle as represented at 17 and 18 for suspending the plate or bridge 12 in the desired position within the holder. The retaining plate 12 is centrally apertured as represented at 14 and has projecting from opposite sides thereof the tongues 15 and 16 angularly disposed with respect to the plane of the plate or bridge 12 to enable the plate to be centered within the piezo electric crystal holder for preventing excess or undesired movement of the piezo electric crystal which is represented at 10. An electrode 9 is employed in contact with the upper surface of the piezo electric crystal 10, which electrode is prevented from moving beyond a given limit established by the plane of the retaining member or bridge 12. Electrode 9 is connected through a flexible lead 11 with the upper cover plate 4 which serves as one electrode for establishing connection with the piezo electric crystal element within the holder.

Connection is established with the plate members 3 and 4 by a device shown at 20 having arms 21 and 22 which embrace the opposite sides of the piezo electric crystal holder and establish frictional contact with plates 4 and 3, respectively. Flexible strap member 23 which houses the flexible conductors 24 and 25 is provided to establish electrical connection with the contact arms 21 and 22 which in turn establishes connection with plates 4 and 3, thereby completing the electrical circuit to the piezo electric crystal element.

The insulated frame 1 is made thick enough to hold low frequency crystals with the retaining member or bridge 12 maintained in position by the proper length of arms 15 and 16. When high frequency crystals, which are much thinner, are employed the retaining member 12 must have supporting arms which are substantially longer than the arms when cut for crystals of greater thickness.

It will be observed that the bridge member

12 is easily removable and that for each holder there may be provided a plurality of bridge members having arms of different lengths, which will be easily interchangeable, and will accommodate crystals of different thicknesses. It will therefore be possible to use this type of holder as a universal crystal holder, simply substituting the bridge member corresponding to a given thickness of crystal, instead of requiring a separate holder for each thickness of crystal. It will be observed that no restriction is placed upon the piezo electric crystal element 10 as to its natural vibration characteristic, for there is a sufficient gap between the retaining member 12 and the upper electrode 9 of the piezo electric crystal apparatus to allow free movement of the piezo electric crystal element 10 and the securing therefrom of maximum piezo electric effect. However, under conditions of excess movement of the crystal, such as might occur when the crystal holder is subjected to shock or rough handling during shipment, breakage of the crystal is prevented by prevention of displacement of the crystal beyond a safe limit.

While I have described my invention in a certain preferred embodiment, I desire that it be understood that no limitations upon my invention are intended other than are imposed by the scope of the appended claims.

What I claim as new and desire to secure by Letters Patent of the United States is as follows:

1. In a piezo electric crystal apparatus, an insulated frame structure, a plurality of metallic plates forming walls closing opposite sides of said frame structure, a piezo electric crystal element having one of its faces resting in contact with one of said plates, an upper electrode resting in contact with the other face of said piezo electric crystal element, and a removable retaining bridge member extending substantially parallel to said electrode and supported from opposite points in said frame structure for preventing excess movement of said piezo electric crystal element within said apparatus.

2. A piezo electric crystal apparatus comprising an insulated frame structure, metallic plates forming walls closing opposite sides of said frame structure, a piezo electric crystal element having one of its faces resting in contact with one of said plates, an electrode resting in contact with the opposite surface of said piezo electric crystal element, and a removable retaining bridge member extending in a plane parallel to but spaced from said electrode for preventing excess movement of said piezo electric crystal element with said apparatus.

3. A piezo electric crystal apparatus comprising a frame structure of insulating material, metallic plate members closing the top and bottom of said frame structure, a piezo electric crystal element having one of its faces resting in contact with one of said metallic plate members, an electrode resting in contact with the opposite face of said piezo electric crystal element, retaining means depending from said frame structure in a position immediately adjacent said electrode for preventing excess movement of said piezo electric crystal element within said frame structure.
4. A piezo electric crystal apparatus comprising a frame structure of insulating material, metallic plate members closing the top and bottom of said frame structure, a piezo electric crystal element having one of its faces resting in contact with one of said metallic plate members, an electrode resting in contact with the opposite face of said piezo electric crystal element and a removable retaining bridge member supported from the opposite interior walls of said frame structure and having a portion thereof extending in a plane substantially parallel to the upper surface of said electrode for preventing excess movement of said piezo electric crystal element within said frame structure.
5. A piezo electric crystal apparatus comprising a frame structure of insulating material, metallic plate members closing the top and bottom of said frame structure, a piezo electric crystal element having one of its faces resting in contact with one of said metallic plate members, an electrode resting in contact with the opposite face of said piezo electric crystal element, a retainer member comprising a central portion substantially conforming in contour to the contour of said electrode, tongues extending from opposite sides of said central portion, said tongues projecting into sockets formed in the opposite interior walls of said frame structure for maintaining said retainer member in position above said piezo electric crystal element in such manner as to be easily removable from said sockets and preventing excess displacement of said element.
6. A piezo electric crystal apparatus comprising a frame structure of insulating material, metallic plate members closing the top and bottom of said frame structure, a piezo electric crystal element having one of its faces resting in contact with one of said metallic plate members, an electrode resting in contact with the opposite face of said piezo electric element, a removable retainer member supported by said frame structure and extending to a position immediately above said electrode, said retainer member being centrally apertured to permit the passage of a connection from said electrode to the upper metallic plate member while preventing ex-
- cess movement of said piezo electric crystal element within said frame structure.
7. In a universal piezo electric crystal holder, a frame structure of insulating material, metallic plate members closing the top and bottom of said frame structure, a removable piezo electric crystal having one of its faces resting in contact with one of said metallic plate members, an electrode resting in contact with the opposite face of said piezo electric crystal element, said frame structure having sockets in opposite points thereof, and a removable bridge member having a flat portion and supporting arms adapted to engage said sockets, the arms of said bridge member being of length conformable to the thickness of crystal employed, whereby said bridge member is supported adjacent to said electrode for preventing excessive movement of said crystal.

ARTHUR M. TROGNER.
